UNITED STATES PATENT OFFICE.

FREDERICK W. H. JAHN, OF LOS ANGELES, CALIFORNIA.

OIL-BURNER.

SPECIFICATION forming part of Letters Patent No. 734,712, dated July 28, 1903.

Application filed January 24, 1902. Serial No. 91,118. (No model.)

To all whom it may concern:

Be it known that I, FREDERICK W. H. JAHN, a citizen of the United States, residing at Los Angeles, in the county of Los Angeles and State of California, have invented a new and useful Oil-Burner, of which the following is a specification.

This invention relates to oil-burners; and some of the objects of the invention are to produce a device of this character which will be simple and cheap in construction and at the same time efficient for the purpose intended.

Another object of the invention is to provide an apparatus for burning oil, whereby a portion of the oil first introduced into the apparatus is utilized, and to volatilize the oil subsequently so introduced to effect the operation of the burner, which is designed to burn the volatilized oil.

Another object of the invention is to provide means for accurately determining and regulating the supply of oil to the burner.

With these and other objects in view the invention consists, essentially, in the construction, combination, and arrangement of parts, substantially as more fully described in the following specification and illustrated in the accompanying drawings, in which—

Figure 1 is a front elevational view, partly broken away, of an oil-burner embodying the invention. Fig. 2 is a similar view of a modified form of construction, one of the cups being shown in section. Fig. 3 is a fragmental top plan view of the construction shown in Fig. 1. Fig. 4 is a top plan view of the construction shown in Fig. 2, with the parts above the burners removed. Fig. 5 is a detail view of the valve and indicating devices; and Figs. 6 and 7 illustrate modifications of the constructions before illustrated.

Similar characters of reference designate corresponding parts throughout the several views.

Referring to the drawings, and particularly to Figs. 1, 3, and 5 thereof, the reference character 1 indicates a needle or other suitable valve, upon the stem whereof is secured, by means of a clamp 2, a pointer or index 3, constructed to travel over a segmental or other indicator 4, having a clamp-hub 5, adapted to be movably connected with the body portion or cas-

ing of the valve, so as to remain stationary thereon, and the indicator-plate 4 is preferably provided with numerals or characters and with the words "Open" and "Closed," by means of which the position of the valve can be visually understood or known.

The valve 1 will be connected with a suitable supply-pipe having communication 1^a with a source of supply of the oil and having an elbow 6 connected with the upper portion of a receiver or vaporizer 7, preferably constructed with a rib 8 and lugs or projections 9 to support a deflecting-plate or spreader 10 in a removable manner, and connected with the bottom of the receiver or vaporizer 7, which bottom is preferably sloping or inclined to facilitate the deflection or spreading of heat from the burners, are depending burner-pipes 11, carrying elbows 12, connected with burners 13, which may carry depending pipes or rods 14, connected with the oil-burning cups 15. By means of this construction the oil is admitted through the needle-valve 1 into the receiver 7, from which it passes through the burner-pipes 11 to the burners 13 and flows therethrough and down into the cups 15, whereupon the oil in the cups is ignited and the flame and the heat therefrom volatilizes the oil in descending through the apparatus, and the volatilized oil is burned from the orifice of the burners 13, as will be readily understood.

In order to provide a draft or current of air for the burners, a diaphragm or plate 16 is suitably mounted above the burners and is provided, preferably, with depending sleeves 17, through which the flame from the burners passes, as the sleeves 17 are located directly above the burners.

Referring now to Figs. 2 and 4, there is illustrated a modified form of the construction before described and shown, wherein a single pipe 18 is connected with the central portion of the receiver or vaporizer and is provided with an elbow 19, connected with a T 20, supporting burner-pipes 21, connected with the burners 13, supporting the cups 15, as before described.

The operation of this invention will be readily understood from the foregoing description when taken in connection with the accompanying drawings and the following

explanation thereof: When it is desired to light the burner, it is only necessary to turn the stem of the valve 1 so that the index 3 will pass from over the word "Closed" to and over the numerals "1," "2," "3," and until a sufficient amount of oil shall have been admitted into the receiver or vaporizer 7, from whence it flows down through the pipes 11 to the burners 13 and out through the burners into the 10 cups 15, where it is ignited and the flame and heat therefrom passes up around the burners and adjacent parts to volatilize the oil therein and convert the same into a gas to be burned at the orifices of the burners, 15 as will be readily understood.

It is not desired to confine this invention to the specific construction, combination, and arrangement of parts herein shown and described, and the right is reserved to make all 20 such changes in and modification of the same as come within the spirit and scope of the invention.

Referring to the construction shown in Fig. 6, there is a receiver or vaporizer 7, having a 25 depending burner-pipe 18, located at one edge of the bottom of the receiver and terminating in a T 20, connected by elbows 23 with the burners 13, which may be of the construction before described and may be provided with 30 cups 15, and in one of the burner connections there may be located a valve or cut-off 24, so that one of the burners may be shut off without extinguishing the flame from the other burner.

35 The receiver or vaporizer 7 may be provided with removable plugs 25 to afford access to the interior of the receiver, and the latter may be also provided with an elbow 6 to receive supply connections and with a burner 40 or other device 26 to be used for illuminating purposes, if found desirable in practice.

The construction shown in Fig. 7 is made wholly from pipes, and the receiver or vaporizer 7 is dispensed with, and a T-head 27 is 45 provided, having a connection 28 with a T 29, with which is connected a coupling 30, attached to a valve 31, having an inlet 32 for

the supply-pipe, and with the T 29 is connected a burner-pipe 18, having a reducer-collar 33, connected to a short pipe 34, attached to an elbow 35, connected with the burner 13.

The operation of the modified forms of construction is similar to that first described, and further description thereof will not be required.

I claim—

1. A burner provided with a vaporizer having supply connections and ribs or lugs projecting laterally therefrom, a deflecting-plate 60 removably secured about said vaporizer by said lugs, burners connected to said vaporizer, a diaphragm mounted between the burners and vaporizer and sleeves in said diaphragm depending over said burners. 65

2. A burner provided with a vaporizer having side and end lugs or ribs, supply connection entering one portion of the vaporizer, depending burners connected with the other portion thereof, drip-cups below the burner, 70 a deflecting-plate extending about the vaporizer and supported on said lugs or ribs, a solid diaphragm between the burner and vaporizer and sleeves in said diaphragm extending over said burners. 75

3. A burner provided with a vaporizer having side and end lugs or ribs, supply connection entering one portion of the vaporizer, depending burners connected with the other portion thereof, drip-cups below the burner, 80 a deflecting-plate extending about the vaporizer and supported on said lugs or ribs, a solid diaphragm between the burner and vaporizer, sleeves in said diaphragm extending over said burners and a valve immediately 85 adjacent to the burner to control the same without affecting the other burner.

In testimony whereof I have signed my name to this specification in the presence of two subscribing witnesses.

FREDERICK W. H. JAHN.
